US00D842636S

(12) **United States Design Patent** (10) **Patent No.:** **US D842,636 S**
(45) **Date of Patent:** **** Mar. 12, 2019**

(54) **GRILL**

(71) Applicant: **Hestan Commercial Corporation**,
Anaheim, CA (US)

(72) Inventor: **Raymond Nilssen**, Fairhope, AL (US)

(73) Assignee: **Hestan Commercial Corporation**,
Anaheim, CA (US)

(**) Term: **15 Years**

(21) Appl. No.: **29/611,318**

(22) Filed: **Jul. 20, 2017**

Related U.S. Application Data

(60) Division of application No. 29/556,320, filed on Feb. 29, 2016, now Pat. No. Des. 812,424, which is a continuation-in-part of application No. 29/550,112, filed on Dec. 30, 2015, now Pat. No. Des. 815,484.
